UNITED STATES PATENT OFFICE

110,559

DESIGN FOR A CONTAINER CLOSURE

Rudolph Bernhardt, Chicago, Ill.

Application May 28, 1938, Serial No. 77,451

Term of patent 14 years

To all whom it may concern:

Be it known that I, Rudolph Bernhardt, a citizen of the United States and resident of Chicago, in the county of Cook and State of Illinois, have invented a new, original, and ornamental Design for a Container Closure, of which the following is a specification, reference being had to the accompanying drawing, forming part thereof.

In the drawing:—

I claim:

The ornamental design for a container closure, as shown.

RUDOLPH BERNHARDT.
